DISPLAY DEVICE

Ernest R. Ranucci, Fanwood, N. J.

Application April 22, 1957, Serial No. 654,240

3 Claims. (Cl. 40—30)

The present invention generally relates to a display device and more particularly to a device that is eye-catching so that merchandise displayed therein will be observed by prospective purchasers.

An object of the present invention is to provide a display device incorporating in its construction a pair of spaced, vertically aligned disks, with one disk being rotatable in relation to the other and the peripheries of the disks being interconnected by a series of flexible and elastic members, whereby oscillation of one of the disks will cause sequential expansion and contraction of the elastic cords, thus forming a dynamic pattern which is eye-catching, thus permitting merchandise to be displayed within the confines of the elastic cords.

Another important object of the present invention is to provide a display device which is extremely simple in construction, eye-catching, well adapted for its intended purposes and relatively inexpensive to manufacture.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

Figure 1 is a perspective view of the display device of the present invention;

Figure 2 is a side elevational view of the present invention;

Figure 3 is a plan sectional view taken substantially upon a plane passing along section line 3—3 of Figure 2, showing the details of the driving mechanism; and

Figure 4 is a plan sectional view taken substantially upon a plane passing along section line 4—4 of Figure 2 illustrating the construction of the bottom plate.

Referring now specifically to the drawings, the numeral 10 generally designates the display device of the present invention which includes a bottom, stationary, circular disk or plate 12 supported rigidly with a bottom portion or arm 14 of a supporting bracket 16. The upper end of the supporting bracket 16 is provided with an upper arm 18 in parallel relation to the lower arm 14, with a depending shaft 20 being journaled in a bearing 22 depending from the arm 18 and held thereon by a collar 24. On the lower end of the shaft 20 is an upper circular disk or plate 26 being disposed in vertical alignment with the bottom plate 12.

Also supported on the arm 18 is a motor 28 of the electric type having a rotatable plate 30 driven thereby with a connecting arm 32 being attached to the plate 30

2

by an eccentric 34. The other end of the arm 32 is connected to an upstanding eccentric 36 on the upper disk 26, whereby rotation of the plate 30 will cause oscillation of the disk 26 about the axis of the shaft 20. By varying 5 the position of the eccentrics 34 and 36 and the dimensions of the arm 32, the scope of oscillation of the upper disk 26 may be varied.

Extending between the disks 26 and 12 is a plurality 10 of elastic cords 38, with these cords extending through the plates and connected thereto adjacent the peripheral edge 15 of the plates or disks and being disposed in circumferentially spaced relation. Figure 2 illustrates the normal position of the elastic cords 38 when they are in parallel relation. However, actuation of the motor 28 will cause 20 oscillation of the upper disk 26, thus causing sequential or alternating expansion and contraction of the elastic cords as illustrated in Figure 1, thus forming a pattern which is eye-catching, and any merchandise disposed on the upper surface of the bottom disk 12 within the confines of the 25 pattern formed by the cords 38 will be observed by prospective customers, thus advertising the merchandise in a highly successful manner.

It is pointed out that any mechanism may be employed 25 for supporting the disk, with the supporting mechanism and driving mechanism being normally hidden from view, thus further lending to the eye-catching ability of the device.

The foregoing is considered as illustrative only of the 30 principles of the invention. Further, since numerous modifications and changes will readily occur to those skilled in the art, it is not desired to limit the invention to the exact construction and operation shown and described, and accordingly all suitable modifications and equivalents may be resorted to, falling within the scope 35 of the invention as claimed.

What is claimed as new is as follows:

1. A display device comprising a stationary bottom plate, an upper plate rotatable with respect to said stationary plate, a plurality of elastic cords extending between the peripheral edge portions of the plates in circumferentially spaced relation, and means for oscillating 40 said upper plate, thereby causing alternating expansion and contraction of the elastic cords and alternating expansion and contraction of the cylindrical space enclosed by

45 the cords for drawing attention to merchandise displayed on the bottom plate.

2. The combination of claim 1 wherein said plates are 50 circular, with the upper plate being suspended from a support arm.

3. The combination of claim 1 wherein said oscillating means includes an electric motor having a circular plate mounted on the drive shaft thereof, a connecting arm having one end eccentrically pivotally connected with the plate on the drive shaft of the motor and the other end eccentrically connected with the upper plate, thereby 55 causing oscillation of the upper plate in relation to the lower plate.
